[57] CLAIM

The ornamental design for a sprayer trailer, as shown.

DESCRIPTION

FIG. 1 is a perspective view of a sprayer trailer, showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view thereof; and

FIG. 7 is a bottom plan view thereof;

FIG. 8 is a perspective view of a second embodiment of the design of FIG. 1;

FIG. 9 is a top plan view of FIG. 8;

FIG. 10 is a right side elevational view of FIG. 8;

FIG. 11 is a front elevational view of FIG. 8;

FIG. 12 is a rear elevational view of FIG. 8;

FIG. 13 is a left side elevational view of FIG. 8; and

FIG. 14 is a bottom plan view of FIG. 8.

The cross line shading which is partially shown on all of the tires is understood to repeat uniformly across the circumscribed area.

FIG. 1
